(57) **CLAIM**

The ornamental design for an analytical test cartridge, as shown and described.

DESCRIPTION

FIG. 1 is a perspective view of an analytical test cartridge.

FIG. 2 is top view thereof.

FIG. 3 is a side view thereof; and,

FIG. 4 is a bottom view thereof.

The broken lines depict portions of the analytical test cartridge that form no part of the claimed design.

1 Claim, 4 Drawing Sheets

FIG. 1

FIG. 2

FIG. 3

FIG. 4
